(74) *Attorney, Agent, or Firm* — Posternak Blankstein & Lund LLP

(57) **CLAIM**

The ornamental design for electrosurgical forceps, as shown and described.

DESCRIPTION

FIG. 1 is a perspective view of an embodiment of electro-surgical forceps.

FIG. 2 is a top plan view of the electrosurgical forceps of FIG. 1.

FIG. 3 is a bottom plan view of the electrosurgical forceps of FIG. 1.

FIG. 4 is a right side elevation view of the electrosurgical forceps of FIG. 1.

FIG. 5 is a left side elevation view of the electrosurgical forceps of FIG. 1.

FIG. 6 is a distal end elevation view of the electrosurgical forceps of FIG. 1.

FIG. 7 is a proximal end elevation view of the electrosurgical forceps of FIG. 1.

FIG. 8 is a top plan view of a variant of the electrosurgical forceps of FIG. 1 having a shorter blade length; and, FIG. 9 is a top plan view of a variant of the electrosurgical forceps of FIG. 1 having a longer blade length.

1 Claim, 4 Drawing Sheets
